CLAIM

We claim a new design for a bead retention tray, as shown and described.

DESCRIPTION

FIG. 1 is a side view of a bead retention tray, showing our new design;

FIG. 2 is another side view thereof;

FIG. 3 is a top view thereof;

FIG. 4 is a bottom plan view thereof; and,

FIG. 5 is a front isometric view thereof.

The broken lines in the drawings depict portions of the bead retention tray that form no part of the claimed design.

1 Claim, 4 Drawing Sheets
